UNITED STATES PATENT OFFICE.

GEORGE D. ROPER, OF ROCKFORD, ILLINOIS.

DESIGN FOR A TOP FOR GAS-STOVES.

SPECIFICATION forming part of Design No. 24,753, dated October 15, 1895.

Application filed August 8, 1895. Serial No. 558,694. Term of patent 3½ years.

To all whom it may concern:

Be it known that I, GEORGE D. ROPER, a citizen of the United States, residing at Rockford, in the county of Winnebago and State 5 of Illinois, have invented and produced a new and original Design for a Top for Gas-Stoves, of which the following is a specification, reference being had to the accompanying drawings, in which—

10 Figure 1 is an isometrical representation of my new design. Fig. 2 is an edge view of the same.

One of the leading features of my design consists in the stove-top formed with holes for 15 the cooking utensils and irregular-shaped perforations located in the spaces between the holes.

Another leading feature is the forming of

the top grates flush with the upper face of the stove-top.

The stove-top 1 is of square or rectangular form, fitted to be secured to the main portion of the stove. The top has a series of holes 2 for the reception of the cooking utensils. The spaces of the top between the holes are provided with irregular-shaped perforations 3. The top-grates 4 for the holes are flush with the upper face of the stove-top.

I claim as my invention—

The design for the top of a gas-stove herein 30 shown and described.

GEO. D. ROPER.
